[57] CLAIM

The ornamental design for an ampere-volt-wattmeter or
the like, as shown and described.

DESCRIPTION

FIG. 1 is a top and left front perspective view of an
ampere-volt-wattmeter or the like showing my new
design with the probe in the opened position;

FIG. 2 is a bottom and right rear perspective view
thereof;

FIG. 3 is a left side elevational view thereof with the
probe in the closed position;

FIG. 4 is a front elevational view thereof;

FIG. 5 is a right side elevational view thereof;

FIG. 6 is a rear elevational view thereof;

FIG. 7 is a top plan view thereof; and

FIG. 8 is a bottom plan view thereof.
